UNITED STATES PATENT OFFICE.

JOHN F. POPE, OF OTTUMWA, IOWA.

NECKTIE-FASTENER.

SPECIFICATION forming part of Letters Patent No. 335,716, dated February 9, 1886.

Application filed May 14, 1885. Serial No. 165,450. (No model.)

To all whom it may concern:

Be it known that I, JOHN F. POPE, of Ottumwa, in the county of Wapello and State of Iowa, have invented certain new and useful 5 Improvements in Scarfs for Neck-Wear, of which the following is a full, clear, and exact description.

This invention relates to the construction and arrangement of the various parts of the 10 frame of a scarf for neck-wear and its covering, whereby the scarf may be adjusted and retained in position, and the frame removed from its holder without injury to the outer covering or scarf proper.

15 The invention consists in a slotted plate adapted to be attached to the collar-button, and in a frame for the scarf adjustably attached to the slotted plate.

The invention further consists in bands provided with metal stiffening, and in details of 20 construction of parts and combinations of the same, as will be hereinafter described and claimed.

Reference is to be had to the accompanying 25 drawings, forming part of this specification, in which similar letters of reference indicate corresponding parts in both the figures.

Figure 1 is a rear elevation of a scarf for neck-wear constructed according to my invention. Fig. 2 is a central vertical section of 30 the same.

A indicates the interior shield or frame of the scarf, which may be of any desired form or contour, and to which the covering or scarf 35 proper is to be attached.

C is a plate, preferably of metal, slotted longitudinally at H, and provided at its upper end with a loop, O, for the collar-button. The hollow internally-threaded stem or shank 40 F of a stud or button, D, is passed through the slot H of the plate C, through an aperture in the shield A, and through the covering J, the button D resting against the plate C.

A stud or button, G, which may be of any 45 ornamental design, is provided with a threaded stem, E, which stem is screwed into the threaded shank F of the button D, and se-

cures the shield A, with its covering J, to the plate C.

By unscrewing the stem of the stud G the 50 scarf can be adjusted higher or lower on the plate C, the shank F moving in the slot H of plate C, and by screwing up the stem of the stud G the various parts are clamped between the stud G and the button D, and the scarf is 55 held at the desired point.

Upon the inner face of the plate C neck-bands L are secured, which bands are provided with metal stiffeners M, said bands, with their stiffeners, being pivoted to the 60 upper corners of plate C, so that they can be passed around or beneath the collar and bent to conform to the neck of the wearer. Additional stiffening-strips may be used between the strip M and the covering of the 65 band L. The bands L may be of any desired or suitable length, short ones being preferred. Instead of the clamping device D G shown and described any other well-known clamping device can be used.

The adjustment of the scarf upon the holder provides for scarfs of different sizes being used with the same holder, as well as for the 70 adjustment of the scarf in the desired position.

If preferred, the head D of the clamping device may be made smaller, and a washer placed between it and the face of the plate C, covering the slot H therein, which would be 75 a modification of Fig. 2.

Having thus described my invention, what I 80 claim as new, and desire to secure by Letters Patent, is—

1. The combination, with an interior shield, A, or foundation of a scarf for neck-wear, of 85 an independent exterior slotted plate, C, and clamping device constructed, substantially as described, so that the interior plate, with the scarf thereon, may be adjusted upon the independent exterior plate and clamped, as set 90 forth.

2. The combination, with the interior shield or foundation of a scarf for neck-wear, of an independent exterior slotted plate, C, and

detachable clamping device, substantially as described, which passes through the interior shield, A, and through the exterior slotted plate, to clamp the whole together, as set forth.

3. The combination, with the plate A, of the slotted plate C, adapted to be attached to a collar-button, and of the button D, having internally-threaded stem F, and the stud G, to having a threaded shank, as set forth.

4. In a scarf for neck-wear, in combination with the plate C, the bands L, having metal stiffeners M, substantially as described.

JOHN F. POPE.
